UNITED STATES PATENT OFFICE

GEORGE GRAFF, OF TOLEDO, OHIO, ASSIGNOR TO THE DURA COMPANY, OF TOLEDO, OHIO, A CORPORATION OF OHIO

DESIGN FOR A COMBINATION FOUNTAIN PEN HOLDER AND BASE

Application filed March 30, 1931. Serial No. 39,294. Term of patent 14 years.

To all whom it may concern:

Be it known that I, GEORGE GRAFF, a citizen of the United States of America, residing at Toledo, in the county of Lucas and State of Ohio, have invented a certain new, original, and ornamental Design for a Combination Fountain Pen Holder and Base, of which the following is a specification, reference being had therein to the accompanying drawing, forming a part thereof, in which the figure is a perspective view of a combination fountain pen holder and base, showing my new design.

The essential feature of my design consists in the wavy outline of the tray receiving portion.

I claim:

The ornamental design for a combination fountain pen holder and base substantially as shown and described.

GEORGE GRAFF.
